UNITED STATES PATENT OFFICE.

JESSE H. KRIDER, OF BUTLER, PENNSYLVANIA.

CLOTHES-LINE REEL.

1,052,487.

Specification of Letters Patent. Patented Feb. 11, 1913.

Application filed April 5, 1912. Serial No. 688,776.

To all whom it may concern:

Be it known that I, JESSE H. KRIDER, a citizen of the United States, residing at Butler, in the county of Butler and State of Pennsylvania, have invented certain new and useful Improvements in Clothes-Line Reels, of which the following is a specification, reference being had to the accompanying drawings.

10 This invention relates to new and useful improvements in clothes line reels and has for its primary object to provide a construction which can be readily attached to the side of a house, post or other stationary object and which will be adapted to readily draw in the clothes line and receive the same when not in use, also permitting the line to be positioned at varying angles, as the occasion may require, for supporting the clothes.

20 Another object of the invention is the provision of a clothes line reel upon which the line will be adapted to wind and unwind from the reel or drum confined within a receiver and which is controlled by means of a helical spring so that when the line is withdrawn or unwound from the reel the spring is placed under tension, the tension of the spring tending to rotate the drum and rewind the line when the same is released, the receiver being pivotally mounted for swinging movement thereby permitting the line to be disposed at varying angles.

25 30

A still further object of the invention is to provide a clothes line reel of the above character which will possess advantages of efficiency and durability, is inexpensive of manufacture and at the same time is simple in construction and operation.

With the above and other objects in view 40 the invention consists in the novel features of construction, combination and arrangement of parts hereinafter more fully described, pointed out in the claim and shown in the accompanying drawings, in which,

45 Figure 1 is a perspective view showing the exterior of the casing or receiver. Fig. 2 is a plan view, the lid or cover being thrown back to disclose the interior of the casing. Fig. 3 is a sectional view on the line 3—3 50 of Fig. 2, and Fig. 4 is a detail perspective view of the U-shaped bracket.

Referring more particularly to the drawings, 1 indicates the receiver or casing which is preferably constructed from wood 55 and may be made in two sections 2 and 3, the section 3 comprising a suitable lid or

cover which is hinged to the upper edge of the body section 2 by means of the hinges 4. Horizontally disposed within the body section 2 is a U shaped bracket 5 having its intermediate portion looped to form an eye 6 which is disposed through the opening 7 in the rear of the casing and adapted to be engaged over the hook member 8 secured to any suitable stationary object. Thus it will 60 be seen that the receiver or casing may be swung to varying angles as the occasion requires. Transversely arranged within the body section is the horizontally disposed shaft 9 upon which is mounted a suitable reel or drum 10. Mounted upon the shaft 9 and arranged adjacent one end of the drum is a pinion 11 adapted to mesh with the gear 12 which is suitably mounted upon the inwardly extending shaft 13, said 70 shaft having one of its ends securely mounted in the side wall of the body section and held in position by the nut 14 threaded upon the end thereof.

Formed integral with one side of the gear 80 wheel is the sleeve 15 adapted to be loosely mounted upon the shaft 13. Mounted upon the sleeve and having one end secured thereto is the helical spring 16, the outer end of said spring being secured to the inwardly 85 extending bolt 17 which is secured at one of its ends to the casing 2 by means of a nut 18 threaded thereon. Thus it will be seen that as the line is withdrawn or unwound from the reel 10, the pinion 11 will rotate the gear 90 12 and place the spring 16 under tension, the tension of the spring tending to rotate the drum and rewind the line when the same is released. To prevent any backward movement of the drum 10 when the line is 95 being unwound therefrom, a ratchet 19 is mounted upon one end of the shaft 9 and arranged upon the outer side of the casing, said ratchet being held securely in place by means of a nut 20 threaded upon the outer 100 end of the shaft. A suitable pawl 21 is pivotally secured to the body section and adapted to engage the ratchet 19 to prevent backward movement of the drum 10. Mounted upon the other end of the shaft 9 is a crank handle 22 which is adapted to rotate the drum 10, when the line has been withdrawn to the required distance to tighten the same, the pawl 21 holding the drum 10 against movement so that the line will be 110 held taut.

In unwinding the line 22' from the drum

10 the same is to be withdrawn from the casing through the opening 23 formed in one end of the body section 2. A suitable hand-hold 24 is secured to the outer end of 5 the line so that the same can be quickly and easily withdrawn from the casing. The hand-hold 24 is provided at its ends with the beveled faces 25 adapted to engage with the beveled faces 26 formed upon the side 10 edges of the opening 23 to prevent the hand-hold 24 from passing entirely into the casing, the same being held in position by the tension of the spring 16 so that it may be easily and quickly grasped to withdraw the 15 line.

When it is desired to suspend the line for supporting clothes, the line is unwound from the drum by grasping the hand-hold 24 and fastening the line to a suitable support 20 which may be located at any required distance from the receiver, the unwinding of the line from the drum 10 placing the spring 16 under tension so that when the line is released the tension of the spring will 25 rotate the drum and rewind the line.

From the above description taken in connection with the drawings, it will be seen that I have provided a novel clothes line reel which is suitably housed within a casing or receiver to protect the clothes line and the reel from rain, sleet, or snow, the receiver being pivotally mounted for swinging movement to permit the line to be disposed at varying angles.

30 While I have shown and described the preferred form of my invention it will be obvious that various changes in the details of construction and in the proportions may be resorted to for successfully carrying the 35

invention into practice without sacrificing 40 any of the novel features or departing from the scope thereof.

Having thus described the invention what is claimed is:

45 In a clothes line reel, the combination of a sectional casing having an opening formed in one end thereof, a U-shaped bracket arranged within the casing, said bracket having its intermediate portion looped to form 50 an eye which is disposed through the opening and arranged upon the outer side of the casing, a rotatable drum mounted within the casing, a helical spring arranged within the casing and adapted to rotate said drum when the same is placed under tension, a 55 line arranged upon said drum, the front wall of said casing formed with an opening, a closure for said opening, the outer end of said line being secured to the inner wall of said closure, a hand hold formed on the 60 outer wall of said closure, said closure adapted to be removed from the opening in the casing and secured to a suitable support at any desired distance from said casing, the 65 said closure adapted to be held in a closed position by an action of said spring, the edges of the said opening and said closure being beveled thereby preventing the closure from passing entirely within the casing, as and for the purpose hereinbefore set 70 forth.

In testimony whereof I hereunto affix my signature in the presence of two witnesses.

JESSE H. KRIDER.
